VENDING MACHINE

William Andrew Harris, Greenville, S. C., assignor
to William D. Young, Greenville, S. C.

Application May 20, 1943, Serial No. 487,719

5 Claims. (Cl. 312—48)

This invention relates to a vending machine and more especially to a vending machine which is compact in size and which will hold a maximum number of articles within the minimum amount of space, and thus will permit the vending machine to be installed in small places where a minimum of room is available, such as on airliners, railway passenger cars, and in fact, in any place where it is desired to have a maximum stock of supplies for sale housed within a minimum amount of space.

It is an object of this invention to provide a vending machine having a rotary circular magazine divided into a plurality of compartments disposed on chords of the circular magazine with means for delivering one article at a time from a compartment until the articles within the compartment are exhausted, together with means for automatically shifting the magazine where another compartment will register with a delivery opening to deliver an article upon the insertion of a coin by moving the magazine to rotate the magazine to thereby move the empty compartment from registering position and to move the next compartment to registering position to deliver an object to the customer.

It is another object of this invention to provide a vending machine having a rotary magazine with a plurality of compartments in said magazine for housing a plurality of objects for sale together with means controlled by an inserted coin and also controlled by an article to be sold for controlling the movements of the magazine.

It is still another object of this invention to provide a coin-controlled vending machine having a magazine provided with a plurality of compartments together with means adapted to engage the magazine when one of the compartments is empty to move the magazine to a new position for the delivery of an article of merchandise from a new compartment.

Some of the objects of the invention having been stated, other objects will appear as the description proceeds, when taken in connection with the accompanying drawings, in which—

Figure 1 is a front elevation of my vending machine;

Figure 2 is a detail elevation view looking from the line 2—2 in Figure 1;

Figure 3 is a view similar to Figure 1, but showing the front cover for the magazine removed and also showing the front cover for the lower part of the machine removed;

Figure 4 is a view similar to Figure 3, but show-

ing the mechanism in a different position, and showing the coin chute in section;

Figure 5 is a vertical sectional view taken along the line 5—5 in Figure 4;

Figure 6 is an enlarged vertical sectional view taken along the line 6—6 in Figure 3.

Referring more specifically to the drawings, the numeral 10 denotes the base piece and 11 indicates the back piece, and 12 and 13 respectively indicate the side walls of the lower portion of the machine. The upper ends of the side walls 12 and 13 are turned outwardly as at 14 and 15, and secured to these outwardly turned portions 14 and 15 is a circular casing 16. The circular casing is secured over the perimeter of the upper circular portion of the back piece 11. Fixedly mounted in the back piece 11 is a shaft 20 which has associated therewith a support 21 secured to the back piece 11. On the shaft 20, there is rotatably mounted a magazine carrying circular disc 22. Secured to the front face of the circular disc 22 are a plurality of spaced parallel vanes 23, these vanes having laterally projecting ledges 24 extending therefrom to partially restrict the front portion of compartments 25 disposed between the vanes 23. In these compartments 25, a plurality of articles for sale 26 are disposed. These articles may be cylindrical as shown, or they may be square or hexagonal or of any other shape. The ends of the compartments 25 are closed by the circular casing 16. The front edges of the vanes 23 may have secured thereto, if desired, a plate 28, as shown in Figure 3, or this plate may be dispensed with, if desired, and a suitable bearing block 33 may be disposed between the two central vanes for rotatably supporting the outer end of the magazine on the shaft 20. A suitable collar 34 is secured on the outer end of the shaft 20 to loosely confine the magazine on the shaft 20 for rotation. The circular casing 16 is cut away from the points 35 and 36 in Figure 4 to allow room for the operating mechanism such as the levers of the vending mechanism which will be presently described. The restricted portions of the casing project inwardly towards each other and are turned downwardly as at 37 and 38, thus providing an opening between the down-turned lips 37 and 38 for the passage of articles of merchandise from the magazine when one of the compartments 25 is in registered position with the opening between the lips 37 and 38.

Secured to the front surface of the vanes 23 is an arcuate member 40 having a plurality of pins 41 therein, by means of which the operating mechanism upon insertion of a coin engages these

pins successively, one at a time, to shift the magazine when one of the compartments therein has become empty of merchandise. On the inner surface of the circular housing 16 there are disposed a pair of stops 42 and 43 which limit the amount of rotative movement which may be imparted to the magazine. Also secured to the outermost vanes 23 are leaf springs 45 and 46 which press against the inner surface of the circular housing 16 and thus apply a braking action to the rotative movement of the magazine to prevent its being turned beyond a given point when it is shifted to present a new compartment to vending position.

A suitable cover for the magazine is provided, comprising an annular member 50 which has bayonet slots 51 therein which are adapted to engage pins 52 and 53 projecting from the outer periphery of the housing 16. A suitable hasp 54 is pivotally mounted in lug 55, and this hasp is adapted to fit over an eyelet or staple member 56 so that a suitable lock can be inserted in staple or eyelet 56 to lock the cover in position to prevent unauthorized removal of the goods from the magazine. The annular member 50 is adapted to support a pane of glass or other transparent material indicated by reference character 57. The upper portion of this pane of glass down to dotted lines 58 has the rear surface thereof provided with a coating of silver to thus provide a mirror while the lower portion thereof below the dotted lines 58 in Figure 1 is transparent so that the goods can be observed through the glass. The annular member 50, as well as the portions of the housing 16 which appear at the upper end of the lower housing 12 are cut away from points 35 to 36 thus providing a slot 60 as shown in Figure 5 for thus allowing freedom of operation of the mechanism disposed within housing 12.

The lower housing formed from side walls 12 and 13 and the base 10 has a suitable cover 65 disposed thereover which is secured to the side walls 12 and 13 in any suitable manner such as by screws, not shown, and this front cover has a coin slot 66 through which a coin can be inserted to pass into the coin slot mechanism disposed within the housing, and which will be presently described. The front cover 65 also has an opening 67 through which the goods are delivered to the customer and an outstanding and downwardly sloping bracket 68 is secured on the exterior of the cover 65, which has an upturned lip 69 at its outer end and spaced sufficiently from the cover to allow the article to come partially through the opening 67 and to engage the projection 69 so as to hold the object delivered in position for the operator to remove it.

Secured on the upper surface of base 10 is a U-shaped bracket 70 having upstanding legs 71 and 72. Rotatably mounted in the upper ends of legs 71 and 72 is a shaft 73. This shaft has handle 74 secured on the end thereof which projects through the cover 65. The shaft 73 has collars 76 and 77 fixedly secured thereon, and secured to the collar 77 is a downwardly depending arm 78 which is adapted to engage a leaf spring 80 secured to the upper surface of base 10. This leaf spring 80 tends to move the shaft at all times to the position shown in Figures 1 and 3. Fixedly secured to collars 76 and 77 are the legs 83 and 84 of an inverted U-shaped member 85. This member 85 has secured between the legs thereof a horizontal portion 87 and immediately below the portion 87 is another horizontal member 88 which extends from leg 83 to leg 84 for a purpose which

will be presently described. Projecting upwardly from the left-hand edge of the horizontal portion 87 is a portion 90 which has integral with the upper end thereof an arcuate platform 91 which has slots 92 and 93 therein. Fixedly secured on the outer surfaces of the legs 83 and 84 are the upstanding bars 95 and 96. Pivotally secured as at 100 to each of the bars 95 and 96 are members 101 which have a weight 102 mounted on one end thereof, at least one of these weights having pins 103 and 104 for limiting the swinging movement of the weights and the mechanism associated therewith. The left-hand end of these members 101 have secured thereto the upstanding legs 105 and 106 of U-shaped member 107. This U-shaped member has rising from the portion 107 upstanding supports 108 and 109, onto which the packages 26 are adapted to fall one at a time as they leave the magazine in the course of their travel to delivery position. Pivotally mounted as at 112 near the upper end of the bar 95 is a magazine moving member 113 which is bent inwardly as at 114 and has portion 115 provided with a vertical wall 116 which is adapted to engage the pins 41, one at a time, to move the magazine to a position which will present a new column of merchandise to vending position when the column of merchandise in any one of the compartments 25 becomes exhausted. Pivotally secured as at 120 is a link 121 which is pivotally secured as at 122 to member 101 nearest the observer or on the front side of the machine. This coordinates the operation of the magazine advancing mechanism along with the control of the same by the presence of a package in vending position.

Rising from the base piece 10 is a bracket 130 which has mounted on the upper end thereof a cross piece 131 and to this cross piece 131, leaf springs 132 and 133 are secured and project rearwardly beneath the transverse member 88 disposed below the horizontal portion 87, and the right-hand end of these leaf springs 132 and 133, as shown in Figure 4, project upwardly and then outwardly to form a support to prevent the articles of merchandise 26 from rolling off of the horizontal member 87 until the mechanism has moved to the position shown in Figure 3, at which time the rear edge of the cross member 88, or the right-hand edge of same, as shown in Figure 4, rides up the inclined portions of these leaf-spring members and depresses same as shown in Figure 3 to allow the article of merchandise to fall by gravity into a sloping trough 140. This trough is supported by a block 141 at one end, and has an upturned lip 142 at its rear end which is secured to the rear wall member 11 as at 143. This sloped trough allows an article of merchandise 26 to slide by gravity outwardly partially through the opening 67 and onto the bracket 68, ready to be picked up by the purchaser. Secured on upstanding leg 71 is an arm 150 and on the upper end of this arm as at 151 is pivotally mounted a lever 152. This lever is adapted to rest normally on a pin 153 on member 95 and the left-hand end of the lever 152, as shown in Figure 4, has a disc member 154 secured thereon which closes one side of the coin chute for supporting the coin until the operating handle is moved. The lever 152 has a shoulder 155 adapted to rest normally against the left-hand edge of the pin 153 when the parts are in the position shown in Figure 3. In this position, the left-hand end of lever 152 is disposed within the path of the coin as it falls down the chute, and in the

absence of a coin, locks the mechanism against delivery of goods. The member 95 also has a pin 156 which limits the upward travel of the right-hand end of lever 152. Pins 156' and 157 are provided in back wall 11 to limit movement of inverted U-shaped member 85.

The coin chute comprises a plate 160 suitably secured to the side wall 13, and this supports the plate 161 which has inturned flanges 162 to assist the plate 161 in guiding the coins downwardly in the chute. There is an opening 163 provided in the plate 161, and the coin after being inserted through the opening 66 in the outer casing then is directed downwardly and inwardly through opening 163 and is then allowed to fall downwardly through the chute. There is a very weak leaf spring 165 secured on the outer surface of wall 161, and this projects through a slot 166 and across the path traveled by the coin. If the coin is of lighter weight than that specified for operation of the machine, the spring 165 will not be flexed sufficiently to allow the coin to continue its downward travel in the chute and will be knocked outwardly to the left in Figure 6, and therefore will never reach the left-hand end of lever 152 in Figure 4 to depress the same. If it is a coin of proper weight, it will knock the spring 165 out of its way and will continue downwardly and fall onto the free end of lever 152, and disc 154 will prevent its lateral discharge, and in this position, the coin will be held to raise the right-hand end of lever 152 in Figure 3, and then as the crank is rotated, the pin 153 riding along the lower side of lever 152, will raise the right-hand end of the same upwardly to a greater degree, and thus lower and withdraw the left-hand end of the lever 152 to a point where the coin will be released to drop into a coin box 170.

The operation of the apparatus is as follows:

The front cover 57 of the magazine will be removed, and the articles of merchandise will be placed into the various compartments 25 through the openings at the upper portions of these compartments where no ledges are present. The articles of merchandise will fall downwardly and will rest against the inside periphery of the circular casing 16. The first article inserted in the first compartment of the left-hand compartment in Figure 3 will fall on downwardly through the opening appearing between the lips 37 and 38, and will rest on the members 108 and 109. This will depress these members, and also will depress the lever 113 to where it will be free and disposed below the adjacent pin 41, and thus will not rotate the magazine. The machine is now ready for operation. When a coin is dropped into the coin slot, the lever 152 is rotated slightly in a counterclockwise manner, but the lever will not be rotated sufficiently to allow the coin to drop into the coin box. In this position, when pin 153 is free to rotate on account of shoulder 155 being moved upwardly, and the left-hand end 115 of lever 113 being in lowered position, the purchaser will seize the handle or crank 74 and rotate it in a counterclockwise manner. This will cause the arcuate platform 91 to move to the position shown in Figure 4, and the first article of merchandise 26 held against rearward movement by lip 38 will fall downwardly onto the portion 87 as shown in Figure 4. This rotation of the handle will further rotate the lever 152 to withdraw its left-hand end from the path of the coin, and from a supporting position for the coin, and will allow the coin to fall into the cash box 170. When the handle is released, the spring 80

will cause the parts to return to the position shown in Figure 3, and the article of merchandise will fall off of the horizontal portion 87 into trough 140 and be delivered through opening 67. 5 As the parts move from the position shown in Figure 4 to the position shown in Figure 3, the pointed ends of the members 108 and 109 will ride between the lowermost article of merchandise to be delivered and the one appearing next above 10 and the second from the bottom article of merchandise as shown in Figure 4 will then rest on the members 108 and 109, and they will be in a depressed position flush with the upper surface of the arcuate platform 91. In this position, the 15 left-hand end 115 of lever 113 will be in lowered position such as shown in Figure 4, and the machine will be ready for another customer.

When a coin is dropped into the machine and the compartment registering with the delivery opening is exhausted of merchandise, and there 20 is no merchandise appearing on the members 108 and 109, these members 108 and 109 will be in elevated position due to the action of the weights 102, and thus the shoulder 116 will be resting as 25 shown in Figure 3, and when a coin is dropped into the machine, and the crank is given a counterclockwise rotation, the shoulder 116 will engage a pin 41 immediately in front of it, and will rotate the magazine to where the lower end of 30 the next compartment will register with the delivery opening, and a package will fall onto the members 108 and 109 and thus release the shoulder 116 from further operation of the magazine until the compartment in registered position has 35 become exhausted. When all of the articles of merchandise in the registering compartment have been sold, the machine will be automatically moved as above described to present the next compartment in registering position, and this will 40 continue until all of the articles of merchandise from all of the compartments have been sold. The left-hand pin 41 will then be resting against the stop 43. In initial position, as shown in Figure 3, when the machine is full of merchandise 45 and none have been sold therefrom, the right-hand pin 41 will be against stop 42, thus the stops 42 and 43 form the outer limits of rotation of the magazine in either direction.

In the drawings and specification, there has 50 been set forth a preferred embodiment of the invention, and although specific terms are employed, they are used in a generic and descriptive sense only and not for purposes of limitation, the scope of the invention being defined in the claims.

55 I claim:

1. In a vending machine having a magazine and a casing surrounding the same, the magazine being movable within the casing and having a plurality of open ended compartments therein, 60 said casing having an opening in the lower end thereof through which an article of merchandise is adapted to pass from a registering compartment, a mechanism housing disposed below the magazine casing and supporting the same, delivery mechanism mounted within said housing and comprising an oscillatable member having upper and lower offset platforms, spring means normally holding the delivery mechanism in a position whereby the upper portion will be disposed below the delivery opening, said magazine having projections thereon, the delivery mechanism having swingable means adapted to engage the projections and move the magazine to cause 65 a succeeding compartment to register with the opening, the upper portion of the delivery mecha- 70 75

nism having pivoted means adapted to be depressed by the weight of an article disposed on the said upper portion for holding the swingable means on the delivery mechanism out of the path of the projections on the magazine, whereby when all of the articles have been exhausted from a given compartment, and no article is present on the upper portion, the swingable means on the delivery mechanism will engage one of the projections on the magazine, and move it one step to cause the next compartment to register with its delivery opening, means for swinging the delivery mechanism cooperating with means restraining lateral movement of the lowermost article to cause an article supported on the upper portion to fall onto the lower portion, and when the delivery mechanism is returned to normal position to fall onto a trough leading to the exterior of the machine.

2. In a vending machine having a circular movable magazine provided with a plurality of compartments disposed on chords of the circle of the magazine, the ends of the compartment being open, a casing surrounding the magazine and preventing articles within the compartments from moving out of the compartments, said casing having an opening in the lower portion thereof through which the articles from a compartment registering with the opening may fall downwardly, mechanism disposed below the opening for supporting a column of articles alined with a compartment registering with the opening, means for moving the magazine to cause a succeeding compartment to register with the opening in the casing when all of the articles alined with a registering compartment have become exhausted, means for controlling the movement of the magazine moving means, said controlling means being controlled by the presence or absence of the article in contact therewith.

3. In a vending machine having a rotary circular magazine disposed on a horizontal axis for holding articles of merchandise, a casing surrounding the magazine and having an opening in its lower portion, said magazine being provided with a plurality of compartments open at both ends and disposed on chords of the circle of the magazine, coin-controlled delivery mechanism for delivering the articles one at a time from the opening to an outlet, means on the delivery mechanism for engaging the magazine, and moving it one step to present the lower end of another compartment in registry with the delivery opening, the last-named means being held in inoperative position by the weight of an article or articles in registry with a compartment and being adapted to engage the magazine and move it to where a succeeding compartment registers with the opening when there are no articles alined with a compartment registering with the delivery opening.

4. In a vending machine having a rotatable circular magazine disposed on a horizontal axis for holding articles, said magazine having a plurality of compartments disposed on chords of the circle of the magazine and being open at both ends, a casing surrounding the magazine, a housing disposed below and supporting the casing for

the magazine and having a delivery opening therein, the casing for the magazine having an opening establishing communication between the lower end of a compartment and the housing, an oscillatable delivery mechanism disposed in the housing and having upper and lower offset platforms, the lower platform being disposed a substantial distance below and to one side of the upper platform and the upper platform being normally disposed below the delivery opening, so that articles in a compartment of the magazine registering the opening will move by gravity downwardly until the lowermost articles rest on the upper platform, means for imparting oscillation to the platforms to move the upper platform from beneath the delivery opening and to position the lower platform below the delivery opening, means for restraining lateral movement of the lowermost article, so that the articles in line with

10 a compartment will move downwardly and be supported by the lower platform, spring means for returning the platforms to normal position to cause the upper platform to move above the lowermost article and below the next succeeding article and to expel the lowermost article from the lowermost platform through the delivery opening in the housing.

5. In a vending machine having a rotatable circular magazine disposed on a horizontal axis for holding articles, a casing surrounding the magazine, an open-topped housing disposed below the magazine and having a delivery opening therein, said casing having an opening establishing communication between the upper portion of the housing and the lower portion of the casing, said magazine having a plurality of compartments disposed on the chords of the circle of the magazine, each compartment being open at both ends and the lower end of a compartment being adapted to register with the opening in the lower part of the casing, a swingable delivery mechanism disposed in the housing and having upper and lower offset platforms, spring means for normally holding the delivery mechanism in a position where the upper platform will be disposed below the lower end of a compartment registering with the opening in the casing, means for swinging the delivery mechanism to move the upper platform from beneath the lowermost article alined with a compartment, means for restraining lateral movement thereof and allowing the lowermost article to fall onto the lower platform of the swingable delivery mechanism, so that when the spring means returns the swingable delivery mechanism to normal position, the upper platform will be moved beneath the next to the lowermost article, and the lowermost article will fall by gravity off of the lower platform and through the delivery opening in the housing, means for engaging the magazine and moving it to where a succeeding compartment will register with the opening in the casing and means penetrable by an article resting thereon for holding the means for moving the magazine in inoperative position.

WILLIAM ANDREW HARRIS.
